UNITED STATES PATENT OFFICE.

ROBERT LEE LEATHERMAN AND FRANK PFRONER, OF MOUNT PLEASANT, PENNSYLVANIA.

COMBINATION DESK AND CHAIR.

1,328,169.

Specification of Letters Patent. Patented Jan. 13, 1920.

Application filed April 22, 1918. Serial No. 230,078.

To all whom it may concern:

Be it known that we, ROBERT L. LEATHERMAN and FRANK PFRONER, citizens of the United States, residing at Mount Pleasant, 5 in the county of Westmoreland and State of Pennsylvania, have invented certain new and useful Improvements in Combination Desks and Chairs, of which the following is a specification.

10 This invention relates to furniture and more particularly to a combination desk and seat.

15 The primary object of this invention resides in the provision of a combination desk and seat which can be adjusted to various heights.

20 Another object of this invention resides in the provision of a combination desk and seat the construction of which is such that the necessity of employing a kit of tools to 25 adjust the same is eliminated.

A further object of this invention resides in the provision of a combination desk and seat consisting of a minimum number of 25 elements which are cheap of manufacture and readily adapted for the purpose of its adoption.

With these and other objects in view this 30 invention resides in certain novel features of construction and arrangement of elements to be more fully set forth in the specification herewith and pointed out in the appended 35 claim.

In the accompanying drawing:—

35 Figure 1 is a side view of a desk and seat constructed in accordance with this invention;

Fig. 2 is a plan view thereof;

40 Fig. 3 is a side view of a desk and seat showing a modified form of construction;

Fig. 4 is a detail section view on line 4—4 of Fig. 3.

45 In the present embodiment of this invention the numeral 21 designates the main standard having the bolt ears 24, 24, and 22' an auxiliary standard. The main standard has the parallel spaced slots, 6, 6, while the auxiliary standard has the slot 25. The slots 6, 6 are arranged for the reception of 50 cleats 8 that are secured to a desk 10 to maintain its rigidity with the standards when adjusted to the desired height.

55 In order to facilitate the adjustment of the desk, a rack 12 is secured in any suitable position thereto for engagement with a gear

14 that is secured to a shaft 16 journaled in the standards. This shaft has a ratchet wheel 17 secured thereto for coaction with a pawl 18 to retain the gear in an immovable position after having actuated the rack 60 to adjust the desk. Removable or otherwise engaged by the shaft is a handle 19 for manipulating the shaft. As shown in Fig. 2, the desk has the back 22 with its end projecting outward, these ends being 65 clamped between the standards, 5 and 22', whereby the desk is clamped and held in adjusted position.

The aforesaid standards consist of separable sections between which the back 22 70 of the desk is clamped by means of suitable bolts 23 which engage bolt ears 24 formed on the standards.

The sections 22' have grooves 25 formed therein for the reception of slidable blocks 75 26 that are secured by a rod 26' to brackets 27 which are secured to a seat 28.

Pivottally secured to the brackets as at 29 are curved pawls 30 which are utilized to engage arcual notches 31 formed in said sections 22' of the standards to support the seat in an extended position.

With the above construction it is readily apparent that the seat and desk can be adjusted to any desired height and since the 85 standards coact in supporting the desk and seat in their adjusted positions, it is manifest that a simply constructed combination seat and desk is produced.

In the form shown in Figs. 3 and 4, the 90 arcual notches 31 are dispensed with, and other grooves 32 are provided for the reception of other blocks 34 carried by the brackets 27 and secured in the desired adjusted position by pins 35 or the like that 95 pass through apertures 36 in the standards.

With this embodiment of elements it is manifest that the cost of production is reduced without sacrificing the initial advantages as the adjustment of the desk 100 remains as heretofore set forth while the adjustment of the seat is accomplished by extracting the pins 35 and sliding the blocks in alinement with other apertures.

In either disclosure of the seat hinges as 105 at 37 may be provided to permit the same to be folded when unoccupied.

Having thus fully set forth the advantages of this invention, it is manifest that a desk and seat is produced which can be adjusted 110

to comfortably accommodate individuals while occupied at a desk.

Having thus described this invention what we claim is:—

- 5 In a device of the character described, and in combination, a main supporting standard having parallel spaced slots, a shaft held to said standard, a gear on said shaft, a ratchet on said shaft, a pawl secured to said standard in contact with said ratchet, a desk having extending cleats ar-
- 10

ranged to slide in said spaced slots, a rack bar extending from said desk and meshing with said gear, an auxiliary standard, and a back secured to said desk having its ends 15 projecting and clamped between said standards, whereby said desk is held in adjusted position.

In testimony whereof we affix our signatures.

ROBERT LEE LEATHERMAN.
FRANK PFROGNER.
